UNITED STATES PATENT OFFICE.

MAX COLBOW, JR., OF CLEVELAND HEIGHTS, OHIO.

SECRET CABINET.

Application filed December 21, 1923. Serial No. 682,116.

To all whom it may concern:

Be it known that I, MAX COLBOW, Jr., a citizen of the United States, residing at Cleveland Heights, in the county of Cuyahoga and State of Ohio, have invented certain new and useful Improvements in Secret Cabinets, of which the following is a specification.

The present invention relates to a secret safe or cabinet and has for its object to provide a device of this character which embodies novel features of construction whereby it is normally concealed or camouflaged in an effective manner so that the location 10 thereof will not be suspected or discovered by a person not familiar with the secret, and which is at the same time readily accessible to any person knowing the location of the compartment and the manner of opening the 15 same.

Further objects of the invention are to provide a secret compartment or safe which is comparatively simple and inexpensive in its construction, which can be readily built 25 into the wall of a building, which can be easily opened at any time, but which is so effectively concealed that there is no likelihood that any person unfamiliar with the secret will ever discover the location thereof.

With the above and other objects in view, the invention consists in certain combinations and arrangements of the parts as will more fully appear as the description proceeds, the novel features thereof being pointed 30 out in the appended claims.

For a full understanding of the invention reference is to be had to the following description and accompanying drawings, in which—

40 Figure 1 is a perspective view of a secret safe or cabinet which is constructed in accordance with the invention, the door or closure thereof being shown as swung outwardly into an open position.

45 Figure 2 is a rear view of the exposed cabinet which forms the closure for the hidden safe or cabinet.

Figure 3 is a front elevation of the hidden safe or cabinet with the closure removed, 50 portions of the wall being broken away and shown in section to illustrate more clearly the details of construction.

Figure 4 is a horizontal sectional view 55 through the cabinet, the exposed cabinet which forms a closure for the hidden safe or cabinet being shown by full lines in a closed

position and by dotted lines in an open position.

Figure 5 is a vertical sectional view of the line 5—5 of Figure 4, looking in the direction of the arrows, a portion of the back wall of the exposed cabinet being shown as broken away.

Figure 6 is an enlarged horizontal sectional view through one of the side walls of 60 the cabinet, showing the electrically controlled latch member which normally holds the closure of the hidden safe in a closed position.

Figure 7 is a detail view of the spring 70 plunger which causes an initial swinging movement of the closure as soon as the electrically controlled latch member is released.

Corresponding and like parts are referred to in the following description and indicated 75 on all of the views of the drawings by like reference characters.

Referring to the drawings which illustrate one of many possible embodiments of the invention, the numeral 1 designates an opening 80 formed in the face of a wall 2, said opening being shown as arranged between two of the studs 3 which form the frame for the wall. The opening extends into the wall a sufficient depth to provide space for two cabinets, the innermost of which is hidden or 85 concealed by the outer cabinet. The walls of the opening 2 are formed by horizontal cross pieces 4 connecting the studs 3 and upright members 5 connecting the horizontal 90 cross pieces 4. A rear wall 6 is applied to the back of the said frame and provides the back of the secret compartment.

The closure for the opening 1 comprises 95 an outer cabinet 7 which is movable into and out of position, so that access can be had to the rear or hidden compartment at any time when such is desired. The outer cabinet 7 is provided with a frame 8 which extends around the front thereof and projects laterally from the edges of the cabinet, so that it will fit snugly against the face of the wall 2, and effectively conceals the opening 1 when the outer cabinet is swung into position 100 within the opening.

One side of the outer cabinet is connected by a hinge strip 9 to one of the sides of the opening 1. The hinge strip 9 has a width which corresponds substantially with the depth of the outer cabinet and one edge of the strip is hinged at 10 to the back of the outer cabinet, while the other edge thereof 110

is hinged at 11 to an edge of the opening 1. This peculiar mounting of the outer cabinet 7 enables it to be readily swung into either an open or a closed position, as will be readily apparent by reference to Figure 4, in which figure the closed position is indicated by full lines and the open position by dotted lines. The outer cabinet 7 may be provided with the usual shelves 12 and with a door 13 of the conventional character. Likewise the inner and secret compartment may be provided with suitable shelves 14.

When the outer cabinet 7 is swung into a closed position the overhanging frame 8 thereof fits snugly against the wall 2 and effectively conceals the opening 1. This frame 8 is similar in all respects to the usual frame which surrounds a wall cabinet, so that the average observer would quickly notice the exposed outer cabinet, although there is nothing to indicate that this outer cabinet is not permanently and rigidly secured with in the wall in the usual manner. Access can be readily had to the outer cabinet 7 by opening the door 13 thereof, and there is nothing secret about the outer cabinet.

There is nothing visible on the outside or inside of the outer cabinet when the latter is in position within the opening 1 to indicate that the outer cabinet can be displaced to open up an inner and secret safe or cabinet which is located to the rear thereof. It is accordingly extremely improbable that any person not knowing the secret of the location of the hidden safe or cabinet would ever discover the same, even though a careful search were made for the purpose of locating the valuables or articles placed therein.

The use of the hinge strip 9 in mounting the outer cabinet 7 is rendered necessary by reason of the fact that the frame 8 of the outer cabinet overhangs or projects laterally from the edges of the cabinet, so that the pivot center upon which the cabinet swings when it is being opened is almost constantly changing or shifting. Upon the initial opening movement of the outer cabinet the fulcrum point is the edge or corner of the frame 8, and the swinging edge of the cabinet must accordingly have a clearance space such as that which is indicated at 15 on Figures 4 and 6 of the drawings. This clearance space is provided by cutting away or flaring one of the side walls of the frame for the wall compartment. The corresponding upright member 5 of the inner frame has the forward edge thereof beveled or cut away, and an upright strip 16 is fitted against the inner face of the said upright member 5 at the back thereof, the forward edge of the strip 16 being tapered and cooperating with the beveled edge of the upright member 5 to provide the clearance space 15.

This clearance space 15 receives the inner corner of the swinging edge of the outer cabinet 7 upon the initial opening movement of the cabinet and the final closing movement thereof when the outer cabinet is swung into an open or a closed position. Owing to the provision of the clearance space 15 the mouth of the opening 1 is considerably wider than the outer cabinet 7, although the frame 8 of the outer cabinet 75 has a sufficient overhang to extend beyond and completely seal the enlarged mouth of the opening 1 when the outer cabinet is in a closed position.

The back of the outer cabinet is provided at the swinging edge thereof with a latch 17, which is adapted to be engaged by an electrically controlled keeper 18 when the outer cabinet is swung into a closed position, as indicated by Figures 4 and 6. When the latch 17 is engaged by the keeper 18, a filler strip 19 which is applied to the inner edge of the hinge strip 9 engages the adjacent jamb or upright member 5 so that the outer cabinet is held as securely as possible against looseness or lateral movement. Lateral movement of the outer cabinet when in a closed position is also prevented by a pin or stud 20, which projects downwardly from the upper cross piece 4 of the inside frame and engages a notch 21 in the top of the outer cabinet 7, said notch having a flared mouth and contracted rear end, so that when the cabinet is completely closed the stud will interlock with the contracted rear end or base of the notch and tend to prevent any lateral looseness or play of the outer cabinet.

The electrically operated detent or keeper 18 for the latch 17 is adapted to be controlled by a switch 22 which can be located at some distant point, so that an ordinary observer would not suspect any association between the switch and the cabinet. Where the usual electric light circuit is used for the electrically operated keeper, a conventional transformer 23 may be provided for stepping down the voltage in the required manner. When the switch 22 is manipulated the keeper 18 is disengaged from the latch 17, whereupon the outer cabinet 7 is moved outwardly a slight amount by means of a spring plunger 24 which is arranged adjacent an edge of the opening 1 in such a manner as to normally engage the frame 8. This movement of the outer cabinet is sufficient to carry the latch 17 away from the keeper 18, and the operator can then readily grasp the frame 8 with his fingers and swing the outer cabinet into an open position, so that access can be obtained to the inner and secret safe or cabinet. When the outer cabinet 7 is swung back into its original position the latch 17 will be automatically engaged by the keeper 18, and the rear safe 130

or cabinet will then be effectively concealed and hidden so that any valuables or personal papers placed therein will be entirely safe. If desired, the portion of the jamb of

5 the inner frame which is engaged by the latch 17 upon the closing of the outer cabinet may be faced with sheet metal, as indicated at 25, thereby preventing the possibility that the sharp edge of the latch will dig 10 into and injure the wood.

When the outer cabinet is swung into a closed position the rear cabinet or safe is effectively hidden and concealed, although 15 the outer cabinet is mounted in the wall so that it can be used in the same manner as the conventional wall cabinet.

Having thus described my invention what I claim as new and desire to secure by Letters Patent of the United States is,

20 1. A device of the character described including a wall formed with a recess providing an inner cabinet, a movably mounted outer cabinet adapted to close the mouth of the recess, and a latterly projecting frame carried 25 by the outer cabinet and arranged to fit against the wall and conceal the recess when the outer cabinet is in a closed position.

2. A device of the character described, including a wall formed with a recess providing an inner cabinet, a movably mounted outer cabinet adapted to close the mouth of the recess and conceal the inner cabinet, a lock carried by the outer cabinet and inaccessible from the front or interior thereof, said lock serving to hold the outer cabinet in operative position within the mouth of the recess, and distantly located means for controlling the said lock.

35 3. A device of the character described, including a wall formed with a recess providing an inner cabinet, a movably mounted outer cabinet adapted to close the mouth of the recess, the said mouth of the recess being larger than the outer cabinet, laterally projecting frame members carried by the outer cabinet and arranged to fit against the wall and conceal the mouth of the recess when the outer cabinet is in a closed position, and means for holding the outer cabinet against lateral play within the mouth of the recess.

40 4. A device of the character described, including a wall formed with a recess providing an inner cabinet, an outer cabinet adapted to fit within the mouth of the recess, a hinge strip extending along one side of the outer cabinet and having one edge thereof hinged to an inner edge of the outer cabinet while the other edge thereof is hinged to a side of the recess, the mouth of the recess being flared to permit of the outer cabinet being swung into an open and closed position, and means carried by the outer cabinet for covering and concealing 45 the flared mouth of the recess.

5. A device of the character described, including a wall formed with a recess providing an inner cabinet, a movably mounted outer cabinet adapted to close the mouth of the recess, and a stud projecting into the mouth of the recess, the outer cabinet being formed with a notch which is adapted to receive the stud and cooperate therewith to position the outer cabinet and hold it against lateral movement.

6. A device of the character described, including a wall provided with a recess which forms an inner cabinet, a movably mounted outer cabinet adapted to close the mouth of the recess and conceal the inner cabinet, an electrically controlled invisible member inaccessibly located upon the inner cabinet for holding the outer cabinet in a closed position, and a distantly located electric switch controlling the circuit of the said member.

7. A device of the character described, including a wall provided with a recess which forms an inner cabinet, a movably mounted outer cabinet adapted to close the mouth of the recess and conceal the inner cabinet, an inaccessibly located latch for locking the outer cabinet in a closed position within the mouth of the recess, distantly located means for controlling the latch, and means for automatically shifting the outer cabinet toward an open position when the latch is released.

8. A device of the character described, including a wall provided with a recess which forms an inner cabinet, a movably mounted outer cabinet adapted to close the mouth of the recess and conceal the inner cabinet, an inaccessibly latch for holding the outer cabinet in position within the mouth of the recess, electrical means for actuating the latch from a distance, and spring means for automatically shifting the outer cabinet outwardly toward an open position when the latch is released.

9. A device of the character described, including a wall formed with a recess which provides an inner cabinet, an outer cabinet hingedly mounted within the mouth of the recess and adapted to conceal the inner cabinet when in a closed position, the mouth of the recess being flared to permit of the swinging of the outer cabinet into open and closed positions, laterally projecting frame members carried by the outer cabinet and arranged to fit against the wall and conceal the flared mouth of the recess, means for holding the outer cabinet against lateral play within the flared mouth of the recess, an inaccessibly latch for holding the outer cabinet in a closed position, and distantly located means for controlling the said latch.

In testimony whereof, I affix my signature.
